ELEVATOR APPARATUS

William L. Lademann, Bronx, N. Y.

Application February 19, 1931, Serial No. 516,863

9 Claims. (Cl. 187—29)

The objects of this invention are to provide improved apparatus for controlling and indicating the position and direction of travel of elevator cars and to accomplish this with a minimum 5 of wiring and other expense.

The many novel features, combinations and relations of parts comprising the invention and by which the foregoing and other desirable objects are attained, will be understood from the 10 following specification.

The drawings accompanying and forming part of the specification illustrate certain practical embodiments of the invention but it will be apparent that the structure may be modified and 15 changed as regards the present illustrations without departure from the true spirit and broad scope of the invention.

Fig. 1 is a view of two of the "step motor" floor machines and the floor selector which is usually located at the head of the elevator shaft and 20 driven by mechanical means in time with the travel of the elevator, the various electrical connections being indicated diagrammatically and portions of the step motors being broken and appearing in section; Fig. 2 is a front detail of one 25 of the floor indicators; Fig. 3 is a diagrammatic illustration of the zone and floor annunciator system, showing connections from the floor buttons at two of the floors; Fig. 4 is a broken sectional detail illustrating the contact mechanism 30 operated by the selector step motor; Fig. 5 is a diagrammatic view illustrating the elevator control connections and position indicator; Fig. 6 is a broken and partly diagrammatic view of a modified form of step motor control switch 35 mechanism.

Referring to the first sheet of drawings for an understanding of the electric step motor, it will 40 be seen that the same consists of two solenoids or magnets 7, 8, designed to operate cores or ar- 45 matures 9, 10 on the vertically sliding rods 11, 12, guided in suitable brackets or bearings 13 and operating rockers 14, 15, carrying pawls 16, 17, selectively engaging the reversely faced ratchets 18, 19, fast on the shaft 20. The rock levers 14, 50 15 are pivotally supported intermediate their ends as indicated at 21, are slidably connected at their outer ends with the solenoid rods at 22 and have the pawls 16, 17 pivotally mounted on their inner ends at 23, said pawls being thrust inwardly or toward the ratchets by the springs 24, 55 stops 25 on the levers limiting the extent of their inward movement.

In the positions of rest, the ratchets and hence 55 the shaft 20 are retained against accidental or

unintended movement by spring detents 26, 27 on the inner ends of the rocking levers 28, 29 which are connected at their outer ends at 30 with the lower ends of the solenoid rods, the relation being such that the detent which is connected with the inactive magnet serves as a slip detent for the ratchet which is being turned by the active magnet. Thus in the illustration, the detent 26 connected with the left hand magnet engages the ratchet 19 which is being turned by 10 the active or energized right hand magnet. With both magnets de-energized both detents 26, 27 engage the ratchets 19, 18 thus retaining the shaft against turning in either direction. When one magnet is energized, however, the detent which otherwise would hold the shaft 15 against turning in the direction effected by that magnet is released from its holding position and only the detent which serves as a slip detent for rotation in that direction is left in engagement. 20

In Figs. 1 and 2 the step motors are shown as employed for operating the elevator signals at the different floors of a building. In such case, a step motor is located at each floor and connected to operate the signal device at that floor. 25 Thus as shown, the shaft 20 is connected by a pulley and belt 31, 32 or other drive connection with the indicating machine, shown as consisting of the two pulleys 33, 34 on the shafts 35, 36 carrying floor indicating tape 37 which is visible 30 through a window or opening 38 in the casing 39 of the machine, the lamp 40 furnishing the illumination for this indicating portion of the tape. The two shafts of the indicating machine are shown as driven in unison by a belt connection 41 and the upper shaft 35 is shown as carrying 35 a pulley 42 engaged by the belt connection from the step motor.

Thus it will be understood that the floor machines are driven step by step from the motors, 40 to indicate upward or downward travel of the elevator car in accordance with the energization of either the "down" magnets 7 or the "up" magnets 8.

The step by step action of the floor signal 45 motors is governed by a suitable contact machine such as the selector shown in Fig. 1 as consisting of a traveller 43 actuated by the screw 44 driven by gearing 45, or otherwise in accordance with the travel of the elevator car and carrying contact pawls 46, 47 cooperating with contacts 48, 49 in the downward and upward travel respectively of the car.

The "down" set of contacts 48 are shown as connected by suitable wiring 50 with the down set 55

of magnets 7 and the "up" set of contacts are shown as connected by wiring 51 with the up magnets 8. The selector machine is shown as connected to the negative side of the line by 5 wiring 52 and the magnets are returned to the positive side of the line by the wiring 53, the up magnets being connected in a series and similarly the down magnets being in a series relation so that all magnets of one set will be operated 10 simultaneously under control of the selector.

The selector is constructed so that in the travel in one direction only one set of contacts will be operative and correspondingly in the travel of the other direction only the other set will be 15 operative. In the illustration this is accomplished by the provision of insulation 54 on the backs of the contacts 46, 47 which as appears at the top causes the contacts, because of their spring pivot mounting 55, to yield and then snap 20 by without making electrical contact in the movement of the traveller in one direction.

The direction of travel is indicated at the floor machines by the up and down signal lamps 56, 57 which are controlled in the illustration by a 25 rocker 58 on the step motor and actuated by lugs 59, 60 on the solenoid rods to close the down and up signal circuit contacts 61, 62 respectively, the latter being connected by wiring 63, 64 with the down and up signal lamps 57, 56, the latter being 30 connected by the wiring 53 and 55 in the two sides of the line.

While the up and down signal rocker 58 is indicated as mounted on or concentric with the shaft 20, it will be clear that it may be supported 35 in any suitable way for rocking movement under the action of the up and down magnets respectively and it will be understood that it remains in the position to which it is shifted, by friction, spring detent or the like until it is positively 40 shifted in the opposite direction by operation of the other magnets.

After the selector completes each contact, the set of magnets which have just been energized all 45 release their armatures, by gravity, or aided by spring, if that is considered desirable, the weight of the parts, however, usually insuring that the armatures will positively drop and the pawls be released from the ratchets immediately after the circuit is broken at the selector.

50 Figs. 3 and 4 illustrate the employment of the step motor for operation of the "zone" and floor annunciator system. In these views, the step motor is indicated generally at 65, the shaft 20 of the same being shown as carrying an arm 67 55 of insulating material having through contacts 68 to form connection between the two sets of contact rings 69, 70, at the front and the two sets of zone contacts, 71 72, at the back.

The inner set of "down" contact rings 69, are 60 shown connected by wiring 73 with the set of down annunciator signal lights 74 in the elevator car and similarly the outer "up" set of contact rings 70 are shown connected by wiring 75 with the "up" set of annunciator signals 76.

65 The inner set of "down" zone contacts 71 are indicated as connected by wiring 77 with the contacts 78 of the "down" relays 79 and the "up" set of zone contacts 72 are shown as connected by the wiring 80 with the contacts 81 of the "up" 70 control relays 82.

The "down" and the "up" push buttons 83, 84, are connected by wiring 85, 86, respectively with the relays 87, 88 controlling contacts 89, 90. The "down" relays 79, 87, and the "up" relays 82, 88 75 are self-holding magnets so that when energized

by operation of the floor push buttons they will hold their contacts closed until automatically reset by the floor selector mechanism forming part of the usual automatic elevator control and not herein shown.

In the present illustration, if the "up" button 84 on the ninth floor be pressed, a circuit will be closed by wiring 86 through the "up" control relay 88 which will hold its contacts 90 closed until after the car has gone past the ninth floor on its "up" trip. When contacts 90 are closed in this illustration, a circuit will be completed by wiring 91 through the No. 1 zone signal lamp 92 and through the common feeder system 93 to the positive side of the line, the negative side of the line being connected to the other side of the relay switch at 94. A second set of contacts 95 closed by the relay 88 simultaneously with closure of contacts 90 sends current into wiring 80 of the No. 1 set of "up" zone contacts 72 and through 10 contact segments 68 in the carrier segment 67 to the No. 9 contact ring 70 and thence by wiring 15 75 to the No. 9 "up" signal lamp 76 on the annunciator these also being all connected to the common feeder 93. Hence if the car is in the 20 first zone going up, both the No. 1 zone signal and the No. 9 floor signal will show up on the annunciator indicating to the operator of the car a stop on the ninth floor on the up trip. As 25 a further example, if the "up" button were pushed 30 on the 19th floor, the second zone signal 92 would show up at once indicating to the operator a stop in the second zone and as the car passes up into the second zone the No. 9 floor signal would come on to show the operator a stop was to be 35 made on the ninth floor in the second zone, or in other words, the 19th floor of the building and similarly for the third zone floor signals or for any additional zone signals.

The action is reversed for the down travel of 40 the car, the zone signals indicating to the operator stops to be made in the lower zones and the floor signals for such zones coming on as the car passes into such zones on its downward travel. Thus by way of example, if the "down" button 83 45 were operated at the 9th floor, the energization of "down" relay 87 would close one set of contacts 89 to energize the No. 1 zone signal and a second set of contacts 96 to send current by wiring 77 to the No. 9 terminal of the "down" zone contacts 71 and thence to the No. 9 "down" ring contact 69 and by wiring 73 to the No. 9 "down" annunciator signal 74. Similar operations may be traced for the 10th floor in the illustration and it will be understood that the connections may be multiplied for any number of floors. It will be seen furthermore that the zoning system eliminates considerable wiring, it requiring in the 50 illustration only ten wires for "up" signals, ten wires for "down" signals, one wire for each zone 55 and a common feeder, making in this present case only 24 wires to the elevator car for a building of 30 stories.

The step motor 66 for the zone and floor annunciator signals may be located in the motor 60 room, along with the control relays and related parts and is controlled by the floor selector switch mechanism shown at the foot of Fig. 1, which latter preferably also is located in the motor room at the head of the elevator shaft and connected 65 with the up and down and feed circuit wires 97, 98, 99, as will be clear in Figs. 1, 3 and 4. In these views the conditions are illustrated as with the elevator car on its upward travel in the first zone and the selector as having made engagement with 70 75

the No. 9 contact in the "up" series of contacts 49 in the first zone of travel.

In Fig. 5, the control of the elevator is illustrated as effected through the medium of the step 5 motors, one of these motors being located in the motor room as indicated at 100 and another, in step with the first, indicated at 101 on the elevator car. The step motor 100 in the motor room may in fact be built as a part of the zone and floor 10 annunciator step motor 66, Figs. 3 and 4, that is, one step motor be provided for operating both the zone annunciator switch contacts and the switch contacts for controlling the action of the car, which in this case is a so-called "signal-controlled" car, automatically stopping on signals 15 from the floors or from presetting of floor buttons in the car. Thus in Fig. 5, there are indicated a series of automatic buttons 102, in the car adapted to be pressed by the operator of the car 20 as the passengers announce the floors at which they wish to stop, it being understood that a stop button is provided for each floor of the building.

These buttons are shown connected by wiring 103 with contact segments 104 designed to be engaged by a contact 105 carried by an arm 106 on the shaft 20 of step motor 101. This contact 105 on the rotating switch arm receives current from a contact ring 107 connected by wiring 108 with contact ring 109 engaged by contact 110 of switch arm 111 carried by shaft 20 of the control room step motor 100. This switch arm contact 110 at the opposite side engages contacts 112 suitably connected by wiring 113 with the elevator control relays, not shown. Consequently, the closing of the circuit at one of the push buttons in the car automatically effects the stopping of the car when it reaches the floor corresponding to the push button which has been actuated.

The position indicator signals in the car are shown at 114 and these are controlled automatically in Fig. 5 by an extra contact 115 on the step motor switch arm 106 taking current from a contact ring 116 and engaging one after another the contact segments 117 connected respectively with the different floor indicators.

While the construction disclosed in Fig. 4, with the switch arm operating between contact rings on one side and switch contacts at the opposite side after the manner shown in Fig. 4, is satisfactory, all the contacts may be located at one side of the switch arm as in Fig. 6 where said switch arm is shown as carrying elongated switch contacts 105' and 115' adapted to bridge between contact rings 107' and segments 104' and between contact ring 116' and segment 117', respectively.

The use of the step motors materially reduces the necessary amount of wiring in the shaft. It will be seen that for the "signal-control" operation of the car it is only necessary to carry four wires from the control room to the car, this being so because the wiring from the different floor buttons can all be concentrated in the car as shown in Fig. 5, with only the leads from the step motor in the car to the step motor in the control room. The step motors are positioned in action so that once set they will remain in proper step. For the initial setting, they may be individually adjusted by hand and if desired, special synchronizing mechanism may be provided to maintain them in exactly timed relation. These step motors are of simple, sturdy design and relatively inexpensive in construction, and have no parts complicated or fragile which are liable to wear or get out of order. The step motors, furthermore, are adapted to other uses than those shown.

By way of example, instead of the selector switch in the shaft way, illustrated at the bottom of Fig. 1, a step motor may be substituted, operated step by step in one direction by contact switches operated by the car in one direction of travel and rotated in the reverse direction by contact means actuated by the car in its reverse direction of travel.

What is claimed is:

1. In elevator control, the combination of elevator car, floor selecting devices in the car, step by step floor switch mechanism in the car and connected with said floor selecting devices, means for operating said step by step switch mechanism in timed relation with the travel of the car and position indicator signals in the car and controlled by said same step by step switch mechanism on the car.

2. In an elevator system, a step motor, zone and floor indicating car signals for indicating respectively any one of a number of different floor groups and individual floors in each of such groups and control switch mechanism for said zone and floor signals actuated by said step motor to indicate the zone or group in which a call originates and the floor in that group from which such call came.

3. In an elevator system, a step motor, zone and floor indicating car signals for indicating respectively any one of a number of different floor groups and individual floors in each of such groups and control switch mechanism for said zone and floor signals actuated by said step motor to indicate the zone or group in which a call originates and the floor in that group from which such call came and floor signaling devices connected with said zone and floor signal switch mechanism.

4. In elevator systems, switch mechanism actuated by travel of the car in opposite directions, step motors at different floors and connected to be actuated by said switch mechanism in step with the car travel in opposite directions and car position indicator means actuated by said floor step motors, a motor room step motor connected to be actuated in timed relation with the floor step motors and car carried signals actuated by said motor room step motor.

5. In elevator systems, switch mechanism actuated by travel of the car in opposite directions, step motors at different floors and connected to be actuated by said switch mechanism in step with the car travel in opposite directions, car position indicator means actuated by said floor step motors, a motor room step motor connected to be actuated in timed relation with the floor step motors, car carried signals actuated by said motor room step motor and signal-stop control mechanism under control of said motor room step motor.

6. In elevator systems, switch mechanism actuated by travel of the car in opposite directions, step motors at different floors and connected to be actuated by said switch mechanism in step with the car travel in opposite directions and car position indicator means actuated by said floor step motors, a motor room step motor connected to be actuated in timed relation with the floor step motors, car carried signals actuated by said motor room step motor and car carried preset stop means connected to operate in conjunction with said motor room step motor.

7. In elevator systems, switch mechanism actuated by travel of the car in opposite directions, step motors at different floors and connected to

be actuated by said switch mechanism in step with the car travel in opposite directions and car position indicator means actuated by said floor step motors, a motor room step motor connected to be actuated in timed relation with the floor step motors, car carried signals actuated by said motor room step motor, car carried preset stop means connected to operate in conjunction with said motor room step motor 10 and including step motor actuated switch means operating in synchronism with the motor room step motor.

8. In elevator systems, switch mechanism actuated by travel of the car in opposite directions, step motors at different floors and connected to be actuated by said switch mechanism in step with the car travel in opposite directions, car position indicator means actuated by said floor step motors, a motor room step motor connected to be actuated in timed relation with the floor step motors, car carried signals actuated by said motor room step motor, signal-stop control mechanism under control of said

motor room step motor and preset car carried control means connected to be operated in synchronism with the motor room step motor.

9. In elevator control, the combination of an elevator car, floor selecting devices in the car, step-by-step floor switch mechanism in the car and connected with said floor selecting devices, means for operating said step-by-step switch mechanism in timed relation with the travel of the car, position indicator signals in the car 10 and controlled by said same step-by-step floor switch mechanism in the car, switch mechanism actuated by travel of the car in opposite directions, step motors at different floors and connected to be actuated by said switch mechanism 15 in step with the car travel in opposite directions, car positioned indicator means actuated by said floor step motors, control means for stopping the elevator, including a step motor connected to be actuated in timed relation with the floor step 20 motors.

WILLIAM L. LADEMANN.
